PAGE 2

*Fig. 5**Fig. 6*FIGURE 1 is a perspective view of the left side of a telescoping unloading truck showing my design, the front body section being partially telescoped into the lower body section;

FIGURE 2 is a perspective view of the left side of the truck in turning position with the front body section extended forward;

FIGURE 3 is a perspective view showing the front end and right side of the truck;

FIGURE 4 is a perspective view of the rear end of the truck with the tail gate open and the parts fully telescoped together in unloading position.

FIGURE 5 is a perspective view taken from the front and above the truck showing the parts telescoped together in unloading position; and

FIGURE 6 is a top plan view of the truck with the parts in normal load carrying position.

The dominant features of my design reside in the portions shown in full lines.

I claim:

The ornamental design for a telescoping unloading truck, as shown.
